ELECTROLYTIC UNIT

John M. Burkemer and James E. Mason,
Tucson, Ariz.

Application June 29, 1939, Serial No. 281,897

3 Claims. (Cl. 204—248)

Our invention relates in general to electrolytic units for recovering precious metals, such as gold and silver from photographic or other baths. These electrolytic units are electro-couples consisting of layers of different metals, generally copper and zinc, separated by interjacent layers of porous materials, as described in Patent No. 1,425,935, dated August 15, 1922. However, electrolytic units built in accordance with this patent are slow in action and of low efficiency, due to the fact that the metal layers of these units consist of straight, practically equally sized metal strips, arranged in slightly spaced relation parallel and opposite to each other so as to prohibit proper exposure of the metals to the solution, and a proper ratio of exposed surfaces of the metal layers to said solution.

The general object of the present invention is the provision of an improved electrolytic unit of the type referred to above, which acts speedily and is highly efficient by specific construction, size and arrangement of its metal layers.

Another object of the invention is the provision of an electrolytic unit of the type referred to above which includes relatively wide, oppositely arranged zinc plates and a rather narrow strip of copper arranged therebetween opposite the central portion of the zinc plates, the copper strip providing a surface substantially smaller than the surface of each zinc plate so as to effect an efficient ratio of exposed surfaces of the metal layers of the unit.

A further object of the invention is the provision of an improved electrolytic unit of the type referred to with differently sized, alternately arranged layers of zinc and copper which layers are separated from each other by layers of absorbent material, and in which the zinc layers, forming the outer members of the electro-couple, include areas extended beyond the copper layers for better contact of these zinc layers with the solution from which the precious metals are to be reclaimed.

Still another object of the invention is the provision of an electrolytic unit of the type referred to above with zinc layers approximately three times the size of the copper layer, the zinc layers being formed with straight central areas opposite the copper layer and symmetrically arranged wing portions adjacent and angularly related to said central areas, to effect intimate contact of these wing portions with the solution from which precious metals are to be reclaimed.

In addition the invention has certain other marked superiorities which radically distinguish 55

it from presently known structures. These improvements embodying certain novel features of construction are more clearly set forth in the following specification and the appended claims; and a preferred embodiment of the invention is hereinafter shown with reference to the accompanying drawing forming part of the specification.

In the drawing:

10 Fig. 1 is a perspective view of an electrolytic unit embodying the invention, with some of the elements forming the unit shown broken away to more clearly disclose the construction of the unit.

15 Figures 2 through 6 show perspective views of the metal elements of the unit; thus:

Fig. 2 is a perspective view of the shim brass covering for one of the zinc plates;

Fig. 3 is a perspective view of the zinc plate covered by the covering shown in Fig. 1.

Fig. 4 is a perspective view of the copper strip;

Fig. 5 is a perspective view of the other one of the zinc plates, and

Fig. 6 a perspective view of the shim brass covering for the last referred to zinc plate.

20 The electrolytic unit shown in Fig. 1 of the drawing embodies an electro-couple of two zinc plates 3 and 4 and a copper plate 5 arranged between plates 3 and 4 opposite and parallel to the central portions thereof. Each of the zinc plates 3 and 4 has approximately three times the surface of straight copper plate 5 and is subdivided into three substantially equally sized portions, a straight central portion 6 and two wing-like portions 7, 7', arranged adjacent to central portion 6 and angularly offset with respect thereto for a purpose later to be described.

25 The zinc and copper plates 3, 4 and 5 are separated from each other by absorbent material such as cotton gauze 8 which is preferably folded around zinc plates 3 and 4 in such a fashion as to form a pocket 9 between central portion 6 of plates 3 and 4 into which pocket copper plate or strip 5 is kept. As shown, zinc plates 3 and 4 are covered and partly encircled 30 by shim brass sheets 10, which sheets are folded around plates 3 and 4 so as to openly expose their inner central surfaces. Shim brass sheets 10 are also covered with cotton gauze and form neutral depositary elements for precious metals 35 to be recovered from a solution, and the gauze permits of any deposited material being readily stripped or released from these sheets.

40 The thus formed electro-couple is securely tied together by means of a brass band 12 fully encircling same, which band has its overlapping

ends 14 and 15 secured together by a screw member 16, extended through all metal layers to prohibit lateral movements of these layers with respect to each other.

A strip 17 of wood or other suitable non-metallic material secured to the electro-couple by band 12 permits of proper handling and support of the electrolytic unit. When the described electrolytic unit is placed into a photographic fixing solution containing silver in solution the silver will readily be recovered by electro-chemical action of the electro-couple and be deposited on the gauze covered shim brass sheets 18, partly encircling the zinc plates 3 and 4. This recovery action of the unit is rather speedy due to the full exposure of wing portions 7, 7' of zinc plates 3 and 4 to the solution, and such exposure is possible and facilitated by the angular offsetting of wing portions 7, 7' with respect to central portions 6 of the zinc plates.

An electrolytic unit of this type will recover silver of pure bullion standard, particularly, when chemically pure zinc and copper elements are used, and use of chemically pure elements effects rejuvenation of the fixing solution of a bath in a high degree.

Having thus described our invention:

What we claim is:

1. An electrolytic unit for reclaiming precious metals from baths containing such metals in solution comprising a strip of copper, a pair of zinc plates each having a surface area at least twice the surface area of said strip of copper, said zinc plates being arranged at opposite sides of said copper strip parallel thereto and formed with wing portions angularly and outwardly offset with respect to their central portions, layers

of non-conducting porous material spacing said copper strip from the central portions of said zinc plates, and cotton gauze covered sheets of shim brass covering the outer surface of each of said zinc plates and folded around the freely exposed inner surface areas of said zinc plates.

5 2. In an electrolytic unit embodying layers of different metals separated from each other by layers of non-conducting porous material a strip 10 of copper, and a pair of zinc plates, each of said plates having approximately three times the surface area of said copper strip, and embodying a straight central portion equal in size to said copper strip, and symmetrically arranged, integral, angularly and outwardly offset wing portions, 15 said wing portions forming open channels at the opposite edges of said unit to effect more intimate contact of said copper strip and the wing portions of said zinc plates with a solution into which said unit has been placed.

20 3. An electrolytic unit for reclaiming precious metals from baths containing such metals in solution comprising a copper strip, a pair of zinc plates at opposite sides of said copper strip, and 25 a plurality of interjacent layers of nonconducting porous material, the zinc plates each having a surface area at least twice the surface area of the copper strip and being formed with wing portions angularly and outwardly offset with respect to the central portions of said zinc plates 30 to form open channels at opposite edges of said unit and facilitate intimate contact of said copper strip and zinc plates with a solution into which said unit has been placed.
